WARDROBE TRUNK

Herbert N. Williams, Fitchburg, Mass.

Application July 6, 1933, Serial No. 679,193

3 Claims. (Cl. 190—13)

This invention relates to a trunk of the type commonly known as a wardrobe trunk and has for its main object the provision of a generally improved and more satisfactory trunk of this character.

Another object of the invention is the provision of such a trunk so designed and constructed that no parts of the trunk slide over the floor during the opening and closing movements of the trunk, so that the floor will not be marred or scratched during such movements.

Still another object is the provision of such a trunk having means for supporting a closure section of the trunk in substantially horizontal position at an elevation materially above the floor level, and particularly of such supporting means so designed and constructed as to be simple and inexpensive.

To these and other ends the invention resides in certain improvements and combinations of parts, all as will be hereinafter more fully described, the novel features being pointed out in the claims at the end of the specification.

In the drawing:

Fig. 1 is a vertical section taken substantially centrally through a trunk constructed in accordance with a preferred embodiment of the invention, showing the trunk in closed position;

Fig. 2 is a horizontal section substantially on the line 2—2 of Fig. 1;

Fig. 3 is a vertical section through a fragment of the trunk showing it in open position, and

Fig. 4 is an end view of the trunk in the position shown in Fig. 3.

The same reference numerals throughout the several views indicate the same parts.

The trunk of the present invention comprises a main body section 10, and what may be described as a first closure section 11 pivotally connected to the main section 10 by hinges 12 having their axes substantially horizontal at a point materially above the floor level or bottom of the body 10. The trunk also has a second closure section 14 pivotally connected to the body 10 by hinges 15 with horizontal axes substantially at the top of the body section 10. When the trunk is closed, the parts are in the position shown in Fig. 1, with the second closure section 14 overlying and covering the upper end of the main body section 10 and of the first closure section 11.

When the trunk is opened, the section 14 is swung upwardly and backwardly about its hinges 15, and the first closure section 11 is swung outwardly and downwardly about its hinges 12, to a position such as shown in Fig. 3. The hinges 12

will then hold one end of the section 11 at an elevation materially above the floor level.

Means is provided for holding the other end of the section 11 up at substantially the same elevation above the floor level, so that this section will be arranged substantially horizontally when the trunk is open, as shown in Fig. 3. This supplementary supporting means is preferably in the form of a member 20 hinged at 21 to the end 22 of the closure section 11 remote from the hinges 12, and of the proper length so that when it is swung down to the position shown in Figs. 3 and 4, it will contact with and rest upon the floor and hold the section 11 in substantially horizontal position at a material elevation above the floor. When thus held at such an elevation, the section 11 is at a convenient height for packing and unpacking articles in any suitable compartments which may be formed on the inner side of this section, as by means of partitions 25 and 26, for example. A movable flap or cover 32 may be used for holding articles in the compartments.

When the closure section 11 is held up above the floor as here disclosed, a person packing or unpacking articles from the compartments in the closure section does not have to stoop over as far as would be necessary if the closure section rested directly upon the floor, and furthermore, the hinging of the closure section to the main body at a point above the floor level has the advantage that when the trunk is opened, there are no parts which slide over the surface of the floor or which would be apt to mar or injure the floor in any way.

When the trunk is closed, the member 20 is swung over to the opposite side of its hinge 21 so that it occupies substantially the position shown in Figs. 1 and 2. It is placed in this position before the second closure member 14 is closed, and when this member 14 is closed, it then overlies the member 20 so that the latter is wholly within the trunk.

It is to be noted that the member 20 is relatively broad, as shown especially in Figs. 2 and 4, so that it provides a broad base resting upon the floor to furnish an adequate and firm support for the outer end of the section 11.

While one embodiment of the invention has been disclosed, it is to be understood that the inventive idea may be carried out in a number of ways. This application is therefore not to be limited to the precise details described but is intended to cover all variations and modifications thereof falling within the spirit of the invention or the scope of the appended claims.

I claim:

1. A wardrobe trunk comprising a main section, a closure section pivotally connected to said main section at a point materially above the bottom of the main section and extending upwardly from its pivotal connection when in closed position and laterally outwardly from said pivotal connection when in open position, and a supporting member hinged to the end of said closure section remote from said pivotal connection, for movement to an effective position extending downwardly from and acting as a support for said closure section when said closure section is in open position, said supporting member being manually shiftable to another position when said closure section is to be closed.
2. A wardrobe trunk comprising a main section, a closure section pivotally connected to said main section at a point materially above the bottom of the main section and extending upwardly from its pivotal connection when in closed position and laterally outwardly from said pivotal connection when in open position, and a supporting member hinged to the end of said closure section remote from said pivotal connection, for

movement to an effective position extending downwardly from and acting as a support for said closure section when said closure section is in open position, said supporting member being shiftable to an ineffective position wholly within said trunk when said closure member is in closed position. 80

3. A wardrobe trunk comprising a main section, a first closure section pivotally connected to said main section at a point materially above the bottom of the main section and extending upwardly from its pivotal connection when in closed position and laterally outwardly from said pivotal connection when in open position, a second closure section hinged to said main section adjacent the top thereof and adapted to cover the upper end of said main section and of said first closure section when the trunk is closed, and a member hinged to said first closure section and capable of being shifted from an effective position extending downwardly from and acting as a support for said first closure section when said trunk is open, to an ineffective position beneath said second closure section when said trunk is closed. 85 90 95
